FIG. 4

FIG. 1

FIG. 5

FIG. 6

FIG. 3

FIG. 1 is a front elevational view of the combined vehicle bumper and guard, sections of the bumper being omitted to indicate indeterminate length, the remaining portions of the bumper being substantially the same as the portions shown;

FIG. 2 is a top view of the combination of FIG. 1;

FIG. 3 is a bottom view of the combination of FIG. 1;

FIG. 4 is a rear view of the combination of FIG. 1;

FIG. 5 is a view from the right end of the combination of FIG. 1, the view from the left end being substantially identical;

FIG. 6 is a sectional view on an enlarged scale taken substantially along the line 6—6 of FIG. 4.

I claim:

The ornamental design for a combined vehicle bumper and guard, substantially as shown and described.
